UNITED STATES PATENT OFFICE.

PHILIP J. MEAHL, OF CHICAGO, ILLINOIS.

MACHINE FOR MAKING PERFORATED MUSIC.

SPECIFICATION forming part of Letters Patent No. 791,481, dated June 6, 1905.

Application filed March 14, 1903. Serial No. 147,768.

To all whom it may concern:

Be it known that I, PHILIP J. MEAHL, a citizen of the United States of America, and a resident of Chicago, Cook county, Illinois, 5 have invented a certain new and useful Improvement in Machines for Making Perforated Music, of which the following is a specification.

One of the most important features or elements of an automatic piano-player is the sheet of so-called "perforated music," which travels slowly over the tracker-board while the player is in operation.

Generally stated, the object of this invention is to provide an improved and highly-efficient machine for making the said perforated music.

A special object is to provide an improved construction and arrangement whereby the 20 perforations in a pattern or master-sheet may be reproduced in several sheets of paper at a time with great accuracy and with as much rapidity as is practicable in a machine of this character.

Another object is to provide an improved machine of such nature and mode of operation as will permit of the use of an ordinary piece 25 of perforated music as the pattern or master-sheet and which will permit of the use of a master-sheet of comparatively thin paper.

A further object is to provide improved means for insuring an accurate and proper intermittent feeding movement of the master-sheet and also of the paper in which the perforations of the master-sheet are being reproduced and for preventing the maintenance of any tension or pull upon the paper-rolls during the operation of the machine.

It is also an object to provide certain details 40 and features of improvement tending to increase the general efficiency of a machine of this character and tending to reduce the cost of perforated music.

To the foregoing and other useful ends my 45 invention may be embodied in practical form, as hereinafter set forth and claimed.

In the accompanying drawings, Figure 1 is a side elevation of a machine for making perforated music and embodying the principles 50 of my invention. Fig. 2 is a perspective of

a sliding block to which the ends of both the master-sheet and the strips of paper are attached for the purpose of giving the same an intermittent feed, and also of the adjacent portions of the tracks or ways in which the 55 said block slides. Fig. 3 is a longitudinal section through the forward and upper portion of the machine on line 3 3 in Fig. 5. Fig. 4 is a plan of the portion of the machine shown in Fig. 3, certain portions being broken away 60 for convenience of illustration and the lower half of the view being in horizontal section. Fig. 5 is a front elevation of the portion of the machine shown in Fig. 4, the middle portion being broken away for convenience of 65 illustration and the left-hand portion of the master-sheet being broken away for the purpose of exposing to view certain portions to the rear of the master-sheet. Fig. 5 is a perspective of the upper portion of the self-contained element or structure which constitutes the die and the punches, together with the forward end of one of the punch-actuators, the middle portion of the punch and die structure being broken away for the purpose of showing the interior construction. Fig. 7 is a fragmentary perspective view of the upper ends of four of the punch-selecting fingers and also of a portion of the locking-bar for locking the 70 selectors against movement during the operation of the punches. Fig. 8 is a fragmentary perspective view of a portion of the master-sheet, a portion of the tracker-board, and of one of the presser-feet which bear upon the marginal portions of the master-sheet to keep 75 the same in a smooth and proper condition. Fig. 9 is an enlarged side elevation of one of the constantly-vibrating hammers for operating the punches, together with the adjacent portion of the actuating-bar upon which the 80 said hammer or impact device is mounted. Fig. 10 is an enlarged side elevation of the adjustable crank-pin arrangement which constitutes a part of the mechanism for intermittently feeding the master-sheet and paper. 85 Fig. 11 is a section on line 11 11 in Fig. 10. Fig. 12 is a vertical section of one side of the machine on line 12 12 in Fig. 3.

The machine thus illustrated is adapted for reproducing the perforations or openings of 100

a piece of perforated music—such, for example, as a pattern or master-sheet—in one or more strips of paper. In other words, the machine is designed for the purpose of 5 manufacturing perforated music through the medium of a pattern or master-sheet—that is to say, the instrumentalities for making the perforations in the strip or strips of paper are controlled by a perforated sheet of paper 10 which is called a “pattern” or “master-sheet” and which is provided with perforations corresponding substantially, as far as general size and location are concerned, with the perforations to be made in the strip or 15 strips of paper. It is obvious, however, as will hereinafter more fully appear, that the improved arrangement and method of operating the punches may be employed in conjunction with different kinds of patterns or 20 master-sheets and that the punching or perforating instrumentalities may be controlled in various ways without departing from the spirit of my invention. In other words, the hereinafter-described punching or perforating 25 devices, operated by hammers hung on a pivoted support, may be employed in either reproducers or in combination with means for manually controlling the operation of the perforating means.

30 For the purpose of reproducing or manufacturing the perforated music by the aid of a pattern or master-sheet the machine may comprise a suitable body-frame 1, adapted to support the various operative parts in suitably-elevated positions, and adapted to afford suitable bearings for the various shafts and rolls. The unitary and self-contained die-and-punch structure 2 is adapted to extend transversely across the machine and is preferably 35 composed of a base 3, a die-plate 4, provided with a row of die-openings 5, and a pair of bars 6 and 7, separated by distance-pieces 8 and 9 and provided with a plurality of vertically-movable punches 10, corresponding in 40 number and location to the die-openings 5 in the die-plate. These punches are preferably maintained in their normally elevated positions by the springs 11, each spring having one end inserted in the bar 7 and the 45 other end inserted through its allotted punch. As will be observed by referring to Figs. 1 and 3 and also to Fig. 12, the said unitary and self-contained die-and-punch structure is adapted to have its ends extend through openings in the side pieces of the body-frame and is preferably held in place by set-screws 12 and 13. These screws can be inserted through a flange or thickened portion of the frame, extending around the margins of the said 55 60 openings in the sides of the frame. With this arrangement the punches and the die can be removed from and replaced in the machine as a unit. This obviously is of great advantage, as it makes it possible to very easily 65 and readily repair and replace any of the

punches which may become worn or impaired by usage and also to repair or replace the die.

The tracker-board 14 is preferably arranged vertically at the forward end of the machine and substantially in front of the punch-and-die structure. The said tracker-board may consist simply of one or more plates of metal or other suitable material secured at opposite sides to the two side pieces of the frame or body. If desired, the said tracker-board may 70 comprise two plates arranged edge to edge, the edge of one plate being provided with a row of notches. With this construction, the two plates when placed edge to edge, as shown in the drawings, will provide the face of the 75 tracker-board with a horizontal row or series of tracker-board openings 15. In order to hold the pattern or master-sheet perfectly smooth and flat while it travels upwardly over the face of the tracker-board, the forward 80 portion of the frame or body of the machine can be provided with the horizontal bars 16, 17, and 18, arranged substantially as shown in Figs. 3 and 5. The upper bar 16 can be provided with a pair of presser-feet 19, adapted 85 to bear upon the marginal portions of the pattern or master-sheet, while the lower bar 18 can be provided with a similar pair of presser-feet 20. The intermediate horizontal bar 17 90 is preferably provided with a bent plate 21, which also bears upon the pattern or master-sheet from one side to the other and which is provided with a horizontal slot 22, extending opposite and for the full length of the said row or series of tracker-board openings. 95

For the broader purposes of my invention the pattern or master-sheet may be of any suitable known or approved character. Preferably, however, and as a matter of further improvement the said master-sheet 23 is reinforced at its edges or marginal portions by the strips 24, and in addition the thus-thickened edge portions of the master-sheet are provided with teeth 25. These teeth are adapted to engage and mesh with the teeth of the two 100 oppositely - arranged idlers 26, which are mounted upon the face of the tracker-board. In this way the master-sheet is materially strengthened along its edges and marginal portions, and in addition the toothed idlers 105 110 coöperate with the teeth cut in the edges of the master-sheet in insuring a proper and accurate feeding movement. The teeth at the edges of the master-sheet can, it will be understood, be arranged to correspond with the 115 units of feed, the master-sheet, as will herein-after more fully appear, having an intermittent feeding movement in an upward direction upon the face or front surface of the tracker-board. The master-sheet can be fed from the 120 roll 27 at the front of the machine and after passing upwardly across the face of the tracker-board can then be led over the rolls 28, 29, and 30 and thence forward in unison with the sheets of paper. 125 130

The punches are naturally inert or stationary; but the actuators 31 are designed for constant vibration during the operation of the machine, each actuator consisting of a flat bar pivoted or fulcrumed at its rear end upon the shaft or rod 32. These actuators thus mounted for vertical swing or vibration at their forward ends correspond, of course, in number to the punches, the forward end of each 5 actuator being arranged for vertical swing or vibration directly above the upper end of a punch. The shaft or rod 32 can be suitably supported at its ends in the side pieces of the frame or body, as is also the case with the rotary actuating-shaft 33. This shaft 33 is preferably arranged directly above the forward ends of the vibratory actuators and is connected with the rod 34, which passes through the forward ends of the actuators 10 through the medium of a pair of vertically-reciprocating eccentrically-operated pitmen 35. This driving-shaft 33 is adapted for constant rotation during the operation of the machine, and hence the operation of the machine will be accompanied by a constant up-and-down movement or vibration of the actuators 31. Preferably these actuators are, as stated, each in the form of a flat bar and are all strung upon the two rods 32 and 34, 15 their flat sides bearing against each other without any interposed washers or other means of separation. Each actuator is provided at its forward end with a depending hammer or impact device 36, which is pivoted at its upper end in a recess in the lower edge 20 of the actuator and which is of a length to have its lower end occupy a position above and quite near to the upper end of its allotted punch. Preferably the upper end of each 25 hammer or impact device is so pivoted and arranged within the recess that the pivot is relieved of all strain, the upper end of the hammer or impact device bearing directly against the upper end of the top wall of the cavity in which it is pivoted and the said upper end portion being preferably rounded or cut away 30 in the manner shown in Fig. 9. The means through the medium of which the pattern or master-sheet controls the operation of the said 35 punches consists, preferably, of a plurality of vertically-disposed selectors 37. These selectors can have their lower ends strung upon a rod or bar 38, which has its end portions suitably supported in the side pieces of the frame and 40 which thus provides the selectors with a support, about which their upper ends are free to swing. It will be observed that these selectors are arranged in a row immediately back of the tracker-board and that they are 45 subject to the tension of the springs 39, which tend to draw their upper ends forward against the tracker-board. The upper end of each selector is preferably provided with a finger 40, which projects forward from the said upper 50 end of the selector and which is adapted to

pass through one of the openings 15 in the tracker-board and also through the slot 22 in the guard or presser-strip 21. These selectors correspond in number to the openings in the tracker-board and also to the number of 55 punches. In other words, there is a selector for each punch. In order that there may be no lateral movement or sidewise displacement of the upper ends of the selectors, each finger 40 is adapted to accurately fit its allotted 60 tracker-board opening horizontally, but not vertically, and, furthermore, these fingers are preferably slightly narrower than the openings in the master-sheet. In this way it is not possible for the fingers to catch on the 65 edges of the perforations of the master-sheet. Each selector is preferably connected, through the medium of a rod 41, with the hammer or impact device allotted to the corresponding punch. Thus a vibratory or swinging movement of the selector is necessarily accompanied by a vibratory or swinging movement of the corresponding hammer. 70

The upper end of each selector can be provided with notches 42 and 43, adapted to receive the double-beveled knife-edge of the locking-bar 44. This locking-bar is preferably mounted for a partial rotation upon the rod or shaft 45 and is connected with the shaft 46 through the medium of the crank-arms 47 75 and the connecting-rods 48. Another arm 49 on the outer end of this shaft is adapted to engage the periphery of the cam 50, mounted on the driving-shaft 33. This cam is provided with the node 51, whereby the rotation 80 of the driving-shaft will give the shaft 46 an intermittent oscillatory motion, and this oscillation of the shaft 46 will of course result in an intermittent up-and-down movement of the locking-bar 44. Furthermore, the sliding 85 and horizontally-arranged bar 52, which is provided for the purpose of rendering all of the hammers 36 inoperative during the feeding movement of the master-sheet and paper, is also given an intermittent shifting movement from this shaft 46 through the medium 90 of the connecting-rods 53 and the crank-arms 47. This bar 52 can have its ends supported in guideways 54, substantially as shown in the drawings. 95

The intermittent forward feeding movement of the master-sheet is preferably accomplished through the medium of the rotary drum 55, the cable 56, and the sliding block 57. This block is arranged for horizontal sliding movement in the guides 58 and is connected with one end of the cable 56. This rope or cable or other flexible connection preferably extends forward from the said block around the sheave 59 and thence to the said winding- 100 drum. This drum can be given an intermittent rotary movement through the medium of an adjustable crank-pin 60, working in a slot 61 in the upper end of the bar 62, which latter has its lower end fulcrumed or pivoted 105 110 115 120 125 130

upon the shaft upon which the winding-drum is mounted. The vibratory movement of the arm 62 resulting from the rotation of the driving-shaft 33 is converted into an intermittent rotary motion on the part of the drum through the medium of the pawl 63, which is mounted on said arm, and the ratchet-wheel 64, which is mounted on the shaft of the drum. Consequently the rotation of the driving-shaft is, through the medium of the said instrumentalities, converted into an intermittent forward sliding movement on the part of the block 57. The master-sheet after passing over the roll 30 can be brought downwardly and under the winding-drum 55 and can then have its end firmly secured to the small block 65, which is adjustably mounted upon the main block 57. The adjustment of the block 65 can be effected through the medium of the rotary adjusting-screws 66. After the end of the master-sheet is secured to this block 65 the latter can then be properly adjusted so as to take up any slack which might exist in the forward end portion of the master-sheet and so as to insure at the start the proper relation between the master-sheet and the sheets of paper in which the punches are to reproduce the apertures of the master-sheet. As previously stated, the machine is capable of turning out either one or a plurality of sheets of perforated music at a time—that is to say, the punches may operate upon either one or a plurality of superimposed sheets of paper. The forward ends of the strips of paper can be secured to the block 57, as shown in Fig. 1. It will be understood that the guideways thus provided with the sliding block 57 can be of any suitable or desired length. It may be of such length as to make it necessary to have the sliding block 58 travel but once from the machine to the rear end of the guideway during the operation of making several pieces of music, or if this is impracticable then the guideway can be shortened, so that it will be necessary to draw the block back several times and to refasten the master-sheet and paper at different points along their lengths, during the operation of perforating the requisite lengths of paper for any particular musical composition.

The strips of paper can be fed over the roll 67, thence between the bar 7 and the die 4, and thence under the roll 68. The relative arrangement of the roll 67 and the die, as shown in the drawings, can be of a character to insure the requisite amount of tension for keeping the sheets or strips of paper flat and smooth and in their proper relative positions during the progress of their passage over the die and below the punches. Therefore and in order to relieve the feed-rolls 69, upon which the various sheets of paper are mounted, from all injurious strain or draft the power-transmitting connection 70 between the said rolls and the drum-shaft 71 is so ad-

justed that the said rolls and the sliding block 57 operate in unison, each intermittent rotation of the rolls in unison feeding the same amount of paper as is drawn forward by the accompanying forward movement of the block 57. This makes it possible to preserve a certain amount of slack in the paper between the feed-rolls and the roll 67 and to thereby, as stated, relieve the said rolls of all injurious tension or draft. In fact, with this arrangement there is no draft or tension whatever on the paper between the feed-rolls and the roll 67, the tension or friction necessary for maintaining the sheets of paper in a perfectly smooth or flat condition while passing over the die occurring after the paper leaves the roll 67, and if the friction or drag is not sufficient with this arrangement then in such case the roll 67 can be mounted rigidly and held against any rotation whatever. Further friction or drag can be insured by preventing rotation on the part of the roll 68.

It will be readily understood that any suitable power-transmitting connection can be employed for connecting up the feed-rolls 69 with each other and for connecting the rolls thus geared to rotate in unison with the intermittent-feeding shaft 71.

In operation the master-sheet is caused to move upward by steps upon the face of the tracker-board 14, the proper units of feed being determined by adjusting the crank-pin 60. Each time the master-sheet stops the selectors 37 are then released, the fingers of those selectors which are opposite to any perforations in the master-sheet passing through such perforations and carrying certain of the hammers 36 into position to engage the corresponding punches. The locking-bar 44 then engages the notched upper ends of the selectors to hold them against further movement one way or the other, the pressure of the double-beveled edge of the locking-bar in the V-shaped notches in the selectors operating to draw the fingers of those selectors which are not in apertures in the master-sheet slightly away from the surface of the latter and to hold those selectors which are engaging apertures in the master-sheet firmly against movement. The selectors which are not engaging apertures in the master-sheet cause the hammers 36 with which they are connected to remain out of position to engage the corresponding punches, while the selectors which are in engagement with the apertures in the master-sheet hold the other hammers 36 in position to descend upon the upper ends of the corresponding punches. Thus when the actuators 31 descend certain of the punches will be operated, while the balance of the punches will remain in their normal positions. In other words, only such punches as correspond to the hammers connected with selectors engaging apertures in the master-sheet will be driven through the paper and into

the die-openings in the die-plate. Upon further rotation of shaft 33 and upon the rise of the actuators 31 to nearly the limit of their upward stroke the cam-node 51 then strikes 5 the arm 49 for the purpose of rotating the shaft 46, and thereby causing the bar 52 to swing all of the hammers 36 away from the punches and to thereby draw all of the selectors 37 away from the master-sheet. The relative adjustment of the parts is of course such that the bar 44 is lifted just prior to the time 10 at which the bar 52 engages the lower ends of the hammers 36 to pull the selectors away from the master-sheet. As soon as the fingers of 15 the selectors are free from the master-sheet the latter is then given the previously explained intermittent unit of feeding movement, and the selectors are then again released and allowed to swing toward the tracker-board 20 under the tension of the springs 39. Certain of the selectors will then again engage perforations in the master-sheet, while others will encounter imperforate portions of the master-sheet. The locking-bar 44 then immediately 25 engages the selectors to preserve their relative positions during the operation of the punches. The paper 72 is, as previously explained, given an intermittent feeding movement in unison with the master-sheet, and the 30 feeding movement of both paper and master-sheet occurs, of course, during the interval when the actuators 31 are up and the selectors 37 pulled back from the tracker-board.

It will be understood, of course, that the bar 35 52 constitutes a means for rendering all of the hammers 36 inoperative during the feeding movement of the paper and master-sheet and that the selectors constitute the means for determining which of the hammers shall be operated during the downward movement of the actuators 31. Said hammers or impact devices 36 may be regarded as power-transmitting connections between the actuators and the punches which can be rendered inoperative 40 or operative, according to the number of punches to be actuated. These power-transmitting connections between the actuators and the punches can of course be controlled or regulated in various ways. In the present case 45 they are controlled by a master-sheet through the medium of the selectors 37 for the purpose of reproducing perforated music. If desired, however, any other means, either automatic or manual, can be employed for controlling 50 the said hammers.

Inasmuch as the selectors are drawn away from the master-sheet during the feeding movement of the latter, it follows that the said master-sheet can be of comparatively thin paper and that an ordinary piece of perforated music, either in its original form or with slight modification and reconstruction, can be employed as the master-sheet. In other words, 60 the selectors are so well controlled that there 65 is no liability of their tearing or injuring the

master-sheet during the feeding movement of the same.

The presser-feet 19 and 20 can be adapted to bear flatwise upon the master-sheet and also to bear against the inner edges 73 of the reinforcing-strips 29, which are secured to the marginal portions of the master-sheet. In this way these feet or pressing portions act as spreaders to maintain the master-sheet in a perfectly smooth and flat condition while traveling upward across the tracker-board and over the roll 28.

With the increasing popularity of the piano-player it is becoming desirable and, in fact, necessary that the perforated music, which is 80 the most important feature of the player, be sold at as reasonable a figure as possible. A machine of the foregoing character is well calculated to reduce the cost of perforated music without in any way impairing the quality of the latter. In other words, a machine of the character herein described is adapted to produce a high grade of perforated music at a comparatively small cost of manufacture.

With further respect to the unitary and 90 self-contained die-and-punch structure it will be seen that the two guide-bars 6 and 7 can be held together by screws 74 and that ordinary dowel-pins 75 can be employed for preserving the proper relation between these two 95 guide-bars 6 and 7 and the base or body portion 3. In this way the die-and-punch structure as a whole can be easily taken apart and put together.

With further respect to the master-sheet 100 and tracker-board it will be seen that the presser-feet can bear upon the main surface of the master-sheet and also upon the surface of the reinforcing-strips applied to the edges or marginal portions of the master-sheet. The 105 toothed formation of the reinforced edges of the master-sheet, together with the toothed idlers, insure a proper and accurate feeding movement of the master-sheet, it being understood that the teeth on the edges of the 110 master-sheet correspond to or bear a certain predetermined relation to the units of feed. This is a very advantageous feature of my invention, as it insures a proper feeding movement of the master-sheet, as well as a smooth 115 and perfectly flat condition of the same at all times during its upward travel upon the tracker-board.

As previously explained, the herein-described machine is designed for the purpose 120 of reproducing the perforations of a pattern or master-sheet in strips of paper, and in this connection it will be understood that the term "reproducing" is intended to embrace or comprehend, broadly, the manufacture of perforated music by the aid of a pattern or master-sheet regardless of whether or not such pattern or master-sheet has openings of the exact size and location desired for the perforations in the perforated music. In fact, 125 130

the expression "reproducing" as herein used means merely the reproduction, in the form of perforations in a sheet of paper, of the musical composition represented by openings, 5 perforations, or other devices in a pattern or master-sheet. It is obvious, however, that the toothed wheels and the toothed formation of the master-sheet can be used or not, according to the nature of the work and according 10 to the character of the master-sheet to be employed.

By pivotally connecting the rods 41 at points some distance above the lower ends of the hammers it is evident that very slight movement 15 on the part of the selectors is sufficient to give the lower ends of the hammers quite an extent of movement. With the arrangement shown it is also obvious that the selecting and punching operations or actions are 20 of a positive and certain character and of such nature as to permit any desired speed. If the hammers are well finished on their sides, they can then work close together and in such near relation to each other as to practically 25 guide each other in their up-and-down and swinging movements. Furthermore, the blow or impact on each hammer is received practically directly by the member upon which the hammer is mounted rather than by the 30 pivot which carries the hammer. Also it will be seen that the spring - actuated selectors cause the rods 41 to positively pull the hammers into position to engage the punches. In addition the selectors are positively retracted through the medium of the said hammers and rods. 35

Obviously, with the construction shown the unitary punch-and-die structure can be adjusted bodily and horizontally in a direction at 40 right angles to the direction of feed of the paper and master-sheet. The said unitary structure can be adjusted in this manner in order to accurately position the punches below the hammers and can then be held in its adjusted position 45 by means of the set-screws 12 and 13 or by means of any other suitable or desired devices. It will be seen that the punches are organized into a structure which is, by reason of the dowel-pins 75, readily removable as a 50 unit from the structure comprising the die.

I claim as my invention—

1. A machine for making perforated music, comprising a plurality of movable but normally stationary punches, pivoted actuating 55 means adapted for constant vibration about a horizontal axis, a plurality of hammers adapted to vibrate with the said swinging actuating means, and suitable means for collectively or individually bringing the said hammers into 60 operative relation to said punches, said last-mentioned means including a master-sheet and pivoted selectors each having a stationary axis, together with means for retracting said selectors and for causing said selectors to pull the 65 hammers into position to engage the punches.

2. A machine for making perforated music, comprising a plurality of movable but normally inert punches, springs for holding said punches, in their normal positions, a pivoted actuating device adapted for constant up-and-down vibratory movement about a horizontal axis above said punches, a plurality of power-transmitting connections intermediate of said punches and said swinging actuating device, suitable devices for pulling a long sheet of paper beneath said punches and means for either collectively or individually rendering said connections operative or inoperative. 70

3. A machine for making perforated music, comprising a plurality of movable but normally inert punches, a plurality of pendent hammers arranged above said punches and adapted for constant and simultaneous vertical reciprocation, power-transmitting connections for operating said hammers, springs for holding said punches in their normally elevated positions, suitable devices for pulling a long sheet of paper beneath said punches and spring-actuated jointed connections for either individually or collectively pulling said hammers into operative relation to said punches. 80

4. A machine for making perforated music, comprising a plurality of normally inert punches, spring means for holding said punches in their normal positions, a plurality of actuating devices for operating said punches, said actuating devices being adapted and connected for constant operation, and suitable devices including selectors having stationary axes for either individually or collectively bringing 90 said actuating devices into operative relation to said punches, and in accordance with the particular punches to be operated together with means for retracting said selectors, the selectors being spring - actuated and having jointed connection with the actuating devices whereby the selectors pull the actuating devices into position to engage the punches. 100

5. A machine for making perforated music, comprising a plurality of normally inert punches, a plurality of hammers arranged above said punches and mounted for simultaneous and constant vertical reciprocation, a die associated with said punches, feeding devices for feeding paper between the punches and die, a master-sheet, a plurality of selectors associated with said master-sheet and provided with fingers adapted to engage the perforations of the latter, said selectors having stationary axes and suitable jointed connections between said selectors and said hammers, said selectors and master - sheet thereby being adapted to conjointly control the said hammers and to either individually or collectively pull the latter into operative relation to said punches together with means for retracting said selectors. 110

6. A machine for making perforated music, comprising a plurality of normally inert punches, springs for holding said punches in 120

their normally elevated positions, a die associated with said punches, suitable devices for feeding the paper between the die and punches, a plurality of hammers arranged above said punches, a suitably-operated device for causing a simultaneous and constant vertical reciprocation on the part of said hammers, a tracker-board, a master-sheet adapted to travel over said tracker-board, suitable devices for causing said master-sheet to feed simultaneously with said paper, a plurality of selectors associated with said tracker-board and provided with fingers adapted to engage the perforations in the master-sheet, rods connecting the selectors with the said hammers, an intermittently-actuated sliding bar adapted to engage and push the lower ends of said hammers out of alignment with said punches, and to thereby simultaneously pull all of said selectors away from the master-sheet, a locking-bar adapted to engage the upper ends of said selectors, suitable connections between said locking-bar and the said bar which engages the hammers, and power-operated means for causing said instrumentalities to operate in their proper sequence.

7. A machine for making perforated music, comprising a plurality of normally stationary punches and a die organized into a unitary structure, a body-frame having a side opening from which said structure is readily removable as a unit, an actuating device adapted for constant vibratory movement, a plurality of hammers carried by said actuating device and adapted to engage the upper ends of said punches, suitable devices for feeding paper between the die and punches, and suitable devices for either individually or collectively bringing said hammers into operative relation to said punches, said unitary punch-and-die structure being bodily and horizontally adjustable in a direction at right angles to the direction of feed of said paper.

8. A machine for making perforated music, comprising a suitable body-frame having its side provided with an opening, a plurality of normally stationary punches and a die organized into a unitary and self-contained structure which is removable as a unit from said body-frame through said opening, suitable devices for feeding paper between said punches and die, and suitable instrumentalities for controlling the operation of said punches, said unitary punch-and-die structure being bodily and horizontally adjustable in a direction at right angles to the direction of feed of said paper.

9. A machine for making perforated music, comprising a plurality of normally inert punches, spring means for holding said punches in their normal positions, and suitable instrumentalities for selectively operating said punches, said instrumentalities including pendent hammers adapted for constant vibration above said punches together with

selectors and a master-sheet, and a vibrating bar for retracting said selectors, said hammers being mounted upon a swinging support.

10. A machine for making perforated music, comprising a plurality of normally inert punches, a plurality of punch-actuating members adapted for constant vibration said members being mounted upon a swinging support, and suitable instrumentalities for selectively bringing said punch-actuating members into operative relation to said punches, said instrumentalities including a plurality of levers having stationary axes together with means for retracting said levers.

11. A machine for making perforated music, comprising normally stationary punching devices, a plurality of selectors for selectively controlling the operation of said punching devices, suitable devices for feeding the paper to be punched or perforated by said punching devices, a master-sheet associated with said selectors, suitable devices for feeding said master-sheet in unison with the said paper, and a shifting bar connected and arranged for simultaneously retracting all of said selectors preliminary to the feeding movement of the master-sheet and paper.

12. A machine for making perforated music, comprising suitable punching devices, a master-sheet, selectors associated with said master-sheet and adapted and connected for selectively controlling said punching devices, a plurality of rolls for feeding paper to the punching devices, a traveling member to which both the master-sheet and the strips of paper are attached, power-transmitting connections for giving said traveling member an intermittent forward feeding movement, and power-transmitting connections for intermittently rotating said feed-rolls in unison, the power-transmitting connections being so adjusted as to preserve a certain amount of slack on the part of the paper between the feed-rolls and the punching devices.

13. A machine for making perforated music, comprising suitable punching devices, a master-sheet, a plurality of selectors associated with said master-sheet and connected for co-operating with the master-sheet in selectively controlling the operation of said punching devices, a traveling member provided with adjustable means for securing the ends of the master-sheet thereto, and means for securing the paper to be perforated to said traveling member.

14. In a machine for making perforated music, the combination of suitable punching devices, suitable instrumentalities for selectively controlling said punching devices, a plurality of feed-rolls adapted to carry the unperforated paper in roll form and from which to feed the paper to said punching devices, and power-transmitting connections for positively driving the said feed-rolls, the power-transmitting connections being so adjusted as

to preserve a certain amount of slack on the part of the paper between the feed-rolls and the punching devices.

15. In a machine for making perforated music, the combination of suitable punching devices, suitable instrumentalities for feeding paper to said punching devices, and suitable instrumentalities including a master - sheet with thickened or reinforced edges for selectively controlling said punching devices, together with guide - feet engaging said reinforced portions, said guide-feet bearing upon the face of the master-sheet.

16. In a machine for making perforated music, the combination of suitable punching devices, suitable instrumentalities for feeding paper to said devices, and suitable instrumentalities including a master-sheet with toothed edges, together with a pair of toothed wheels engaging said edges, selectors associated with said wheels for selectively controlling said punches.

17. A machine for making perforated music, comprising means for feeding the paper, a horizontal punch-and-die structure, the paper being fed between the punches and the die, and suitable means for operating said punches, said unitary punch-and-die structure being bodily and horizontally adjustable in a direction at right angles to the direction of feed of said paper, the punches being carried by a structure which is removable as a unit from the structure comprising the die.

18. A machine for making perforated music, comprising a plurality of normally stationary or inert punches, a suitable die, a plurality of hammers for actuating said punches, said hammers being carried by the swinging end of a pivoted member adapted for constant vibration during the operation of the machine, and means for selectively controlling said hammers adapted to remain stationary during the operation of the said punches, said controlling means including selectors and a master-sheet, together with means for retracting said selectors.

19. A machine for making perforated music, comprising a plurality of normally stationary or inert punches, a plurality of devices for actuating said punches adapted for constant vibration, and a plurality of levers mounted on a stationary axis and suitably connected for selectively controlling said devices, together with means for retracting said levers through the medium of said actuating devices.

20. A machine for making perforated music, comprising normally stationary means for perforating the paper, normally vibrating means for actuating said perforating means, and periodically-stationary means for selectively controlling said actuating means, said controlling means including selectors and a master-sheet, together with means for retracting said selectors through the medium of said vibrating devices.

21. A machine for making perforated music, comprising a plurality of punches, a die associated with said punches, springs for holding said punches in their normally stationary positions, constantly-vibrating impact devices for actuating said punches, a master-sheet, and a plurality of selectors associated with said master-sheet and having jointed connection with said impact devices, said selectors being adapted to remain stationary during the operation of said punches, together with means for retracting said selectors through the medium of said vibrating devices.

22. A machine for making perforated music, comprising normally inert punching mechanism, normally active pendent hammers for operating said punches, a swinging member on which the hammers are mounted a plurality of pivoted selectors connected for selectively controlling said hammers and adapted to remain stationary during the operation of said punches, and a master-sheet.

23. A machine for making perforated music, comprising a die and a plurality of normally stationary punches, springs for holding said punches in their normal positions, normally vibrating devices corresponding in number to said punches and adapted for operating the latter, a plurality of selecting members also corresponding in number to said punches and having jointed connection with said normally vibrating devices, and a master-sheet, said selecting members being adapted to remain stationary during the operation of said punches, together with means for retracting said selecting members through the medium of said vibrating devices.

24. A machine for making perforated music, comprising normally stationary and inactive punching mechanism, normally active and suitably - operated means for actuating said punching mechanism, a plurality of levers for selectively controlling said punching mechanism through the medium of said operating means, and a master-sheet, said levers being adapted to remain stationary during the operation of said punching mechanism, together with means for retracting said levers through the medium of said normally active means.

25. A machine for making perforated music, comprising normally stationary and inactive punching mechanism, normally active mechanism for actuating said punches, controlling mechanism for selectively controlling the operation of said punches through the medium of said actuating mechanism, and means for retracting certain elements of the controlling mechanism through the medium of certain portions of the said actuating mechanism, said controlling mechanism being adapted to remain stationary during the operation of said punches.

26. A machine for making perforated music, comprising suitable punching devices, suitable actuating devices for operating said

- punching devices, a master-sheet, a plurality of selectors associated with said master-sheet and adapted to selectively control said punching devices through the medium of said actuating devices, said selectors having a stationary axis about which they are adapted to swing and a positively - operated locking device adapted to lock the selectors against movement during the operation of said punches.
- 10 27. A machine for making perforated music, comprising suitable punching mechanism, suitable actuating mechanism for operating said punching mechanism, a master-sheet, selectors corresponding in number to said punches and adapted to control the operation of the latter through the medium of said actuating mechanism, said selectors being arranged to engage the perforations in said master-sheet, and a positively-operated locking device adapted to lock the selectors against movement during the operation of said punches, said locking device being adapted to hold the selectors not engaging perforations away from the surface of the master- sheet during the operation of said punches.
- 15 28. A machine for making perforated music, comprising suitable punching mechanism, suitable actuating mechanism for operating said punching mechanism, a master-sheet, a plurality of selectors associated with said master-sheet and adapted to selectively control the punching mechanism through the medium of said actuating mechanism, and a positively-operated locking device for holding the selectors not engaging perforations in the master-sheet away from the surface of the latter during the operation of the punches corresponding to the selectors engaging the perforations in said sheet.
- 20 29. A machine for making perforated music, comprising suitable punching mechanism and means for operating the same, a master-sheet, a plurality of selectors associated with said sheet and adapted for controlling said punching mechanism, and a positively-operated locking-bar for automatically and positively holding said selectors against movement during the operation of the punching mechanism.
- 25 30. A machine for making perforated music, comprising a die and a plurality of normally stationary and inactive punches, normally active actuating means for operating said punches, a master-sheet and means for feeding the same, a plurality of selectors associated with said master-sheet and adapted for selectively controlling the operation of said punches through the medium of said actuating means, said selectors being adapted to remain stationary during the operation of the punches, and an automatically and positively operated locking device for positively holding said selectors against movement during the operation of the punches.
- 30 31. A machine for making perforated mu-
- sic, comprising suitable punching mechanism involving normally stationary punches, normally active actuating devices for operating said punches, a master-sheet and means for feeding the same, a plurality of selectors associated with said master-sheet and adapted to selectively control the operation of said punches through the medium of said actuating devices, jointed connection between the said selectors and actuating devices, and an automatically-operated retracting device adapted to indirectly retract said selectors through the medium of said actuating devices.
- 35 32. A machine for making perforated music, comprising punching mechanism involving normally stationary punches, normally active actuating devices for operating said punches, means for selectively controlling said punches through the medium of said actuating devices, and an automatically and positively operated locking-bar for locking the controlling means against movement during the operation of the punches.
- 40 33. A machine for making perforated music, comprising punching mechanism, actuating mechanism for operating said punching mechanism, an eccentric-cam shaft for operating the said actuating mechanism, a master-sheet, a plurality of selectors associated with said master-sheet and adapted to selectively control said punching mechanism through the medium of said actuating mechanism, a locking device for positively locking and holding all of said selectors against movement during the operation of said punching mechanism, and means on said shaft for automatically operating said locking device.
- 45 34. A machine for making perforated music, comprising normally stationary punching devices, normally active actuating devices for operating said punching devices, a rotary shaft provided with means for operating the said actuating devices, feeding mechanism for feeding the paper to be punched, means on said shaft for operating said feeding mechanism, a master-sheet, a plurality of selectors associated with said master-sheet and adapted for selectively controlling said punching devices through the medium of said actuating devices, a locking device adapted to hold all of said selectors against movement during the operation of said punching devices, and means on said shaft for operating said locking device.
- 50 35. A machine for making perforated music, comprising normally stationary punching devices, a plurality of normally active and vibratory levers provided with actuating devices for operating said punches, selecting mechanism for selectively controlling said punching devices through the medium of said actuating devices, and means for holding said selecting mechanism against movement during the operation of said punching devices.
- 55 36. A machine for making perforated mu-

sic, comprising normally stationary punching devices, normally active actuating devices for operating said punching devices, selecting mechanism for selectively controlling said punching devices through the medium of said actuating devices, and means for holding said selecting mechanism against movement during the operation of said punching devices.

37. A machine for making perforated music, comprising normally stationary punching devices, normally active actuating devices for operating said punching devices, selecting mechanism for selectively controlling said punching devices, means for holding said selecting mechanism against movement during the operation of said punches, and a horizontal and laterally-shifting bar for engaging and rendering all of said actuating devices inoperative during movements of the selecting mechanism.

38. A machine for making perforated music, comprising a row of punches, a vibratory member, pendent hammers having their upper ends pivotally mounted on said member, a pattern-sheet and means controlled thereby for causing said hammers to engage the punches, each hammer having a shoulder adapted to positively engage the said member and thereby relieve the pivotal connection between the hammer and member from all shock or strain incident to the blow of the hammer upon a punch.

39. A machine for making perforated music, comprising a row of punches, pendent hammers for engaging and operating said punches, a constantly-vibrating member upon which the hammers are mounted, said member being composed of a number of flat plates held flatwise together and each provided at its lower edge with one of said hammers, and means including a pattern-sheet for controlling said hammers.

40. A machine for making perforated music, comprising a row of punches, a row of pivoted hammers arranged close together, said hammers being adapted to engage said punches, a swinging member upon which said hammers are pivoted, means for causing said member to constantly vibrate up and down about its axis, and means including a pattern-sheet and rods pivotally connected with the hammers at points some distance above the

lower ends of the latter and thereby adapted to selectively control the operation of the hammers.

55

41. A machine for making perforated music, comprising a plurality of pivoted levers having stationary axes, springs applied to said levers, a row of punches, a swingingly-mounted member, hammers pivotally mounted on said member and adapted to engage said punches, means for causing said member to vibrate constantly toward and away from the punches, and connecting members pivotally connected with said levers and hammers, whereby said levers may yield to the tension of said springs and thereby pull the hammers into position to engage the punches.

60

42. A machine for making perforated music, comprising a row of punches, a row of pivoted hammers adapted to engage said punches, pivoted levers, each lever being connected by a rod with one of said hammers, whereby each lever when moved in one direction pulls its allotted hammer into position to engage a punch, together with a bar adapted and operative to engage all of said hammers and thereby cause said rods to pull said levers into the desired position.

65

43. A machine for making perforated music, comprising a plurality of punches and a die organized into a unitary structure which is bodily adjustable in a direction lengthwise of the die and row of punches and which is readily removable as a unit from the machine, the punches being carried by a structure which is removable as a unit from the structure comprising the die.

70

44. A machine for making perforated music, comprising a unitary punch and die structure which is bodily adjustable and readily removable as a unit from the machine, and all parts of which are normally stationary, and set-screws for holding said structure in its adjusted position, the punches being carried by a structure which is removable as a unit from the structure comprising the die.

75

Signed by me at Chicago, Cook county, Illinois, this 10th day of March, 1903.

PHILIP J. MEAHL.
